United States Patent

Des. 235,584
Patented June 24, 1975

235,584

KEY HOLDER

Edward M. Hall, 2053 W. Cocopah,
Phoenix, Ariz. 85009

Filed Nov. 7, 1973, Ser. No. 413,585

Term of patent 14 years

Int. Cl. D3—01

U.S. Cl. D87—8

FIG. 1

FIG. 2

FIG. 3

FIG. 4

FIG. 5

FIG. 1 is a perspective view of the front and one side of a key holder showing my new design;

FIG. 2 is a perspective view of the back and other side thereof;

FIG. 3 is a front elevational view thereof;

FIG. 4 is a fragmentary elevational view of the back of the button portion of the key holder; and

FIG. 5 is a side elevational view of the key holder.

I claim:

The ornamental design for a key holder, as shown and described.
